United States Patent Office

Des. 177,355
Patented Apr. 3, 1956

177,355

DISPLAY STAND

Lon L. Wallace, Shoreham, N. Y.

Application January 11, 1955, Serial No. 33,929

Term of patent 14 years

(Cl. D80—10)

FIG. 1.

FIG. 2.

FIG. 3.

I claim:

The ornamental design for a display stand, as shown.
